ACCORDION GRILL

Dorothy K. Traficante, Minneapolis, Minn.

Application October 22, 1953, Serial No. 27,290

Term of patent 14 years

(Cl. D56—1)

To all whom it may concern:

Be it known that I, Dorothy K. Traficante, a citizen of the United States, residing at Minneapolis, county of Hennepin, State of Minnesota, have invented a new, original, and ornamental Design for an Accordion Grill, of which the following is a specification, reference being had to the accompanying drawing, forming a part hereof:

Fig. 1 is a top plan view of an accordion grill showing my new design, an accordion being shown in outline by dotted lines to illustrate the position of the grill thereon;

Fig. 2 is an end elevational view thereof;

Fig. 3 is a front elevational view of the grill per se;

Fig. 4 is a transverse vertical sectional view thereof and taken substantially along the line 4—4 of Fig. 3; and

Fig. 5 is a fragmentary vertical sectional view taken substantially along the line 5—5 of Fig. 1.

I claim:

The ornamental design for an accordion grill, substantially as shown and described.

DOROTHY K. TRAFICANTE.
